(57) **CLAIM**

The ornamental design for an expandable divider as shown and described.

DESCRIPTION

FIG. 1 is a perspective view of a first embodiment of an expandable divider showing my new design;

FIG. 2 is a perspective view from behind thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is a perspective back view of the expandable divider in a retracted state;

FIG. 10 is a perspective front view thereof;

FIG. 11 is a perspective front view of the expandable divider in an environmental use;

FIG. 12 is a perspective back view thereof;

FIG. 13 is an enlarged perspective view of area 13 in FIG. 1;

FIG. 14 is an enlarged perspective view of area 14 in FIG. 1;

FIG. 15 is an enlarged front view of area 15 in FIG. 3;

FIG. 16 is a perspective front view of a second embodiment of the expandable divider with all views identical to that of the first embodiment, except for a perceivable degree of transparency;

FIG. 17 is a perspective view from behind thereof;

FIG. 18 is a front view thereof;

FIG. 19 is a back view thereof;

FIG. 20 is a left side view thereof;

FIG. 21 is a right side view thereof;

FIG. 22 is a top view thereof;

FIG. 23 is a bottom view thereof;

FIG. 24 is a perspective back view of the expandable divider in a retracted state;

FIG. 25 is a perspective front view thereof;

(Continued)

FIG. 26 is an enlarged perspective view of area 26 in FIG. 16;

FIG. 27 is an enlarged perspective view of area 26 in FIG. 16; and,

FIG. 28 is an enlarged front view of area 28 in FIG. 18. Broken lines illustrate environmental elements and/or portions of the expandable divider that form no part of the claimed design.

Double Z shaped lines depict a symbolic break to indicate an indeterminate length. Appearance of any portion between the double Z shaped lines forms no part of the claimed design.

1 Claim, 16 Drawing Sheets

(58) Field of Classification Search
